UNITED STATES PATENT OFFICE.

EDWARD W. HARPER, OF SAVANNAH, GEORGIA, ASSIGNOR OF ONE-THIRD TO
CLARENCE H. KELLY, OF SAVANNAH, GEORGIA.

AUTOMATIC VALVE.

1,384,950.

Specification of Letters Patent. Patented July 19, 1921.

Application filed September 8, 1920. Serial No. 408,845.

To all whom it may concern:

Be it known that I, EDWARD W. HARPER, a citizen of the United States, residing at Savannah, in the county of Chatham, State 5 of Georgia, have invented certain new and useful Improvements in Automatic Valves; and I do hereby declare the following to be a full, clear, and exact description of the invention, such as will enable others skilled in 10 the art to which it appertains to make and use the same.

This invention relates to new and useful improvements in valves and particularly to valves for controlling the supply of water to 15 buildings.

The principal object of the invention is to provide a valve of this character which is automatically closed to prevent freezing of the water in the pipes leading to the building.

Another object is to provide a valve of this character which, while being automatic in its operation to prevent freezing by cutting off the water, may be readily operated by hand.

Other objects and advantages will be apparent from the following description when taken in connection with the accompanying drawing.

In the drawing:

Figure 1 is an elevation of a valve and operating means therefor made in accordance with the invention.

Fig. 2 is a vertical longitudinal central sectional view through the valve and operating mechanism.

Referring particularly to the accompanying drawing, 10 represents the body or casing of the valve in which is arranged a slideable sleeve 11, having longitudinal ribs 12 which engage in grooves in the inner faces 40 of the walls of the neck 13 of the valve casing. The threaded stem 14 of the valve disk 15 is engaged through this sleeve for operation by hand, a hand wheel 16 being carried by the upper end of the said stem. A packing nut 17 is engaged on the upper or bonnet portion of the valve casing, and encircling the stem, between the nut and the hand wheel is a coil spring 18 which exerts upward pressure on the stem to raise the valve 45 from its seat 19, and against the seat 20 formed in the lower end of the bonnet. When it is desired to close the valve by hand, the hand wheel is rotated which will move the stem downwardly through the sleeve 11, 50 and place the valve on its seat 19. The valve

can, however, be closed, when in raised position, by pressing downwardly on the hand wheel against the tension of the spring.

Extending laterally from opposite sides of the valve casing are the arms 21, and disposed vertically through the ends of these arms are the rods 22, screws 23 being engaged in the ends of the arms to retain the rods in proper position therein.

Disposed above the valve is a vertical elongated casing 24 in which is slideable a solid piston 25 having a stem 26 on its lower end which rests on the upper end of the stem 14. A packing nut 27 is engaged on the lower end of the casing 24 around the piston. A pipe 28 connects with the valve casing 10 and with the upper end of the casing 24 for permitting a certain quantity of water to flow from the valve casing into the casing 24 above the piston 25. A relief valve 29 is disposed in the pipe 28, at the point of connection with the casing 24 to permit escape of air when the water in said casing freezes. Connected to the stem of the relief valve is an outwardly projecting arm 30, and pivotally connected to this arm and extending downwardly where it is detachably secured to the stem 26, is an operating rod 31, which is adjustably secured to the stem by the screw 32.

When the valve disk 15 is engaged with the seat 20 the water can pass freely through the valve casing 10, a portion of the water passing upwardly into the casing 24, through the pipe 28. When the water in the casing 24 freezes the expansion forces the piston 25 downwardly with the result that the valve disk 15 will be seated against its seat 19 to cut off the supply of water to the building, and thus prevent freezing of water in the building pipes. At the same time the rod 31 is moved downwardly by the stem 26 so as to open the relief valve 29 and permit the air to be expelled during the expansion of the water in the casing 24. When the ice in the casing 24 melts the pressure is relieved from the spring 18 which immediately expands and moves the piston 25 upwardly into the casing 24 and permits the valve disk 15 to rise to its upper seat 20, when the main valve is open and water is permitted to again flow into the building.

The casing 24 has a pair of oppositely extending arms 24' in which the upper ends of the rods 22 are adjustably supported. By

adjusting the rods 22 through the arms of the valve casing 10 and of the casing 24, the length of the stroke of the piston 25 can be regulated according to the degree of expansion in the said casing, thus regulating the closing of the main valve 15.

What is claimed is:

1. An anti-freezing device comprising a water controlling valve, a casing in which water is adapted to freeze, said valve having a sliding sleeve, the stem of the valve being threadedly engaged through the sleeve for manual opening and closing, a spring for holding the valve normally open and the sleeve in elevated position, and means in the said casing and connected with the valve stem for automatically moving the valve into closed position upon expansion in the casing due to freezing.
2. An anti-freezing device comprising a valve including a casing having a slidable valve and stem therein, a spring for normally holding the valve in open position, a casing located above the valve, arms carried by the valve casing and the upper casing, 25 supporting rods carried by the arms, a piston in the upper casing and bearing on the stem of the valve, a relief valve in the said upper casing, and connections between the relief valve and the said piston for opening 30 the relief valve upon downward movement of the piston to close the valve.

In testimony whereof I affix my signature in the presence of two witnesses.

EDWARD W. HARPER.
